(57) **CLAIM**

The ornamental design for a kettle handle with lever, as shown and described.

DESCRIPTION

FIG. 1 is a top, front, right side, perspective view of a kettle handle with lever;

FIG. 2 is a front elevation view thereof;

FIG. 3 is a rear elevation view thereof;

FIG. 4 is a left-side elevation view thereof;

FIG. 5 is a right-side elevation view thereof;

FIG. 6 is a top plan view thereof;

FIG. 7 is a bottom plan view thereof;

FIG. 8 is a top, front, right side, perspective view thereof, shown with environment; and,

FIG. 9 is a top, front, right side, perspective view thereof, in an alternate position and shown with environment.

In the drawings, the broken lines are for the purpose of illustrating environment only and form no part of the claimed design.

1 Claim, 5 Drawing Sheets
